UNITED STATES PATENT OFFICE

124,720

DESIGN FOR A SHOWER SHOE OR SIMILAR ARTICLE

Lewis Finn, Philadelphia, Pa.

Application September 6, 1940, Serial No. 94,818

Term of patent 7 years

To all whom it may concern:

Be it known that I, Lewis Finn, a citizen of the United States of America, residing in Philadelphia, county of Philadelphia, and State of Pennsylvania, have invented a new, original, and ornamental Design for a Shower Shoe or Similar Article, of which the following is a specification, reference being had to the accompanying drawing, forming part thereof.

Fig. 1 is a bottom plan view of a shower shoe or similar article showing my new design.

Fig. 2 is a side perspective view thereof.

I claim:

The ornamental design for a shower shoe or similar article, as shown.

LEWIS FINN.
